UNITED STATES PATENT OFFICE.

WILLIAM F. LAUTENSCHLAGER, OF CINCINNATI, OHIO, ASSIGNOR TO LORENZ MUTHER, OF NEWTON, MASSACHUSETTS.

FOLDING-MACHINE.

1,399,264.

Specification of Letters Patent.

Patented Dec. 6, 1921.

Application filed May 31, 1919. Serial No. 300,862.

To all whom it may concern:

Be it known that I, WILLIAM F. LAUTENSCHLAGER, a citizen of the United States, residing at Cincinnati, in the county of Hamilton and State of Ohio, have invented a new and useful Improvement in Folding-Machines, of which the following is a specification, reference being had therein to the accompanying drawings.

10 My invention relates to machines for folding the edges of leather, cloth and other pliable material in sheet or band form and more particularly to machines operating in a step-by-step manner and having means for 15 feeding the material in a step-by-step manner, for turning over the edge to be folded and for pressing said turned over edge down upon the body-portion of the material.

Heretofore in the use of such machines, especially for folding the skived edges of 20 leather parts intended for use in boots and shoes, it has been found that the turning over of the edge of the leather while the main portion of the leather remained in a flat position and the use of pressing means having pressing surfaces parallel with the material and the work-support subjected the turned over edge to a strain which prevented the securing of a perfect fold. Furthermore, as a result of the strain imposed upon 25 the edge of the material, the work after being folded, instead of lying flat curved inwardly and sometimes the edge presented a wavy appearance. By slitting the turned 30 over edge, however, a better fold was secured but the slitting on straight edges was a disadvantage because it weakened the folded edge.

To secure better results by obviating the 35 strain on the edge, it has been proposed to use pressing means having pressing surfaces oblique to the work-support of the machine so that the fold might be pressed while held at an angle to the body-portion of the material. The use of pressing means of this character relieved the strain on the edge to some extent but made a crease at the inner edge of the fold which spoiled the appearance of and tended to warp the finished work and 45 which was difficult to remove when the shoe parts were stitched together. At the same time the inward curl of the material, although improved, was not entirely removed. An attempt has been made to remove the 50 crease at the inner edge of the fold and to

prevent warping by providing pressing means arranged to crease the folded edge transversely at the conclusion of the pressing operation but again this is open to the objection that it tends to disturb the cemented 60 relation of the folded edge after it has been folded and to make a heavy bead or fold.

The main object of my invention is the provision in a folding machine of means for supporting the material to be folded in such 65 manner that it may be operated upon by the pressing means without straining the edge and thereby secure a smooth and perfect fold without warping the material.

Another object of my invention is the provision of work supporting, edge turning and edge pressing means so arranged and related to each other that when the work is presented to the pressing means the turned over edge is at an acute angle to the body-portion 70 of the work.

A further object of the invention is the provision of means whereby curves of small radii may be folded with the same degree of precision and nicety that is possible in 75 straight edges.

An additional object is to secure a folding machine of simple and efficient construction which is uniform and positive in its operation and adapted to operate with equal success upon all kinds and classes of work.

Another object of the invention is to provide a slitting device, operable at the will of the operator, for cutting slits in the curved edges of the material, the device being so arranged that the slits are substantially perpendicular to the edge of the material when cut.

Other objects of the invention will be specifically set forth and described in detail 95 hereinafter.

One of the principal features of my invention resides in the provision of a convexly curved work-support and pressing means having a pressing surface parallel to said 100 work-support. Preferably the surface of the work-support is a segment of a cylinder with the axis of said cylinder parallel to the normal line of feed of the material. The pressing means is preferably arranged to operate in a line perpendicular to the curved surface of the work-support. Because of this construction the edge to be folded is turned into an acute angled relation to the body-portion of the material and thereby 105 110

the strain on the edge is entirely relieved which permits the fold to be made evenly and uniformly without warping the material.

5 Another important feature of my invention consists in the particular arrangement of the snipping knife in the machine at an angle to the line of feed of the material so that as the work is pivoted in folding inside curves of short radii, the knife will cut on lines which are approximately perpendicular to the line of curve. Heretofore in folding machines the knife has been arranged perpendicular to the normal line of 10 the feed with the result, however, that on inside curves of short radii, where the work is turned and pivoted around a point, the cuts with a knife so arranged are slanting to the line of the curve. By slanting my 15 knife so that the point is nearer to the operator than the back of the knife, I secure cuts on inside curves of short radii which are substantially perpendicular to the curve and thereby secure, as a result, a more uniform 20 folded edge. The use of a knife on a folding machine is limited, as a rule, to cutting the edge to be folded on inside curves, because it is unnecessary in straight portions and is a disadvantage and is unnecessary on 25 outside curves because the folded edge is simply turned over and plaited.

In the accompanying drawings illustrating the preferred embodiment of my invention, Figure 1 is a side elevation, viewed 30 from the station of the operator, of a folding machine constructed and operated in accordance with my invention; Fig. 2 is an elevation of the machine from the side opposite to Fig. 1 and looking toward the operator; Fig. 3 is a front end elevation of the machine looking from left to right in Fig. 1; Fig. 4 is a plan view of the end of the lower arm with curved work-plate, gage, feed-roll and plow carried thereby; Fig. 5 is a side elevation from the station of the operator of the feeding mechanisms and actuating mechanism therefor; Fig. 6 is a cross-sectional view on line 6—6 in Fig. 5 looking from right to left; Fig. 7 is a cross-sectional 40 view on line 7—7 in Fig. 5 looking from left to right; Fig. 8 is a side elevation, from the view point of the operator, of the curved work-plate, feed-roll, plow and fold-pressing member; Fig. 9 is an elevation from the 45 same point as Fig. 8 of the fold-pressing member and actuating mechanism, Fig. 10 is an end elevation of the slitting mechanism in operating position and Fig. 11 is a plan view of the hammer.

60 In the illustrated embodiment of my invention I have shown a machine having a work-support, the surface of which is a segment of a cylinder with the central axis parallel to the normal line of feed, with suitable means for feeding the material through

the machine, means for turning over the edge to be folded and means for pressing down upon the body-portion of the material the turned over edge, the pressing surface of the pressing means being parallel to the curved work-support. In addition I have shown means for slitting the edge to be folded operable at the will of the operator and so arranged that the cuts on curves of small radii will be substantially perpendicular to the edge.

Passing to a detailed description of the machine shown in the drawings and illustrating the preferred embodiment of my invention, 10 designates a frame having two 80 outwardly extending arms, a lower arm 11 and an upper overhanging arm 12. Upon the ends of these two arms are mounted the various instrumentalities for performing the work; the actuating mechanisms for imparting the necessary motions to such of said instrumentalities as have motion being carried by the frame and the two arms. The frame is provided with a base 14 which may have suitable holes to receive screws where- 85 by it may be fastened to a work bench.

Journaled through the frame at 15 and in a bearing 16 which is supported by webs 17 and 18 depending from and integral with the lower arm 11 at its end, is a main drive 95 shaft 20 having mounted on its rear end a pulley 21, whereby it may be driven by a belt from any suitable source of power.

Upon the upper face of the end of the lower arm 11 is secured by screws 23, 23, a 100 convexly curved work-support 25 which constitutes one of the main features of my invention. The operative surface of this work-support 25 is a segment of a cylinder, the end 26 of the work-support nearest the operator being preferably beveled off to permit the work to be moved forwardly onto the work-support. Although the surface of the work-support is shown as a segment of a cylinder as the preferred form, it is obvious that this form may be varied so long as the work is fed while in a convexly curved rather than a flat position.

The folding instrumentalities consist of a gage 30 for guiding the work through the machine, a fold turner or plow 31 for turning over the edge of the work to be folded, a feed-bar 32 for feeding the work in a step-by-step manner forwardly in conjunction with a feed-roll 33, a presser foot 34 for holding the work between the feeding movements and a fold-presser or hammer 35 for pressing the turned over edge down upon the body-portion of the material and completing the fold. Means for slitting the edge to be folded may also be provided comprising a lower fixed knife block 36 and an upper movable knife 37 co-operating therewith. The gage, plow, feed-roll and knife block are preferably mounted on the lower 120 115 125 130

arm 11 and the remaining parts upon the upper arm 12.

The gage 30 is of usual form comprising a body-portion 30 and an arm 40 having an upright end 41 against which the material is held for guidance in its passage through the machine. The body-portion of the gage is provided with a slot 42 to receive a screw 43 whereby it may be adjustably secured to the top surface of the arm 11.

The fold-turner or plow 31 may be of any suitable construction but as shown is in the form of a block having an oblique curved face like the face of a plow, for turning over the edge of the work as the material is fed forward and by the plow. It is mounted on the end of a flat piece 45 which is secured to the under side of the top of the arm 11 by screws 46 and 47. (See Fig. 4.) The gage and the plow are therefore fixed in their adjusted position. The plow is located a sufficient distance back of the gage to permit of the insertion of a knife blade for slitting the edge when desired.

For feeding the work through the machine a feed-bar 32 and feed-roll 33 are provided. The latter is loosely mounted on the end of the lower arm 11 by means of a screw 50 and washer 51 so that it may revolve freely. The periphery 52 of the feed-roll is oblique to its axis and is curved parallel to the curve of the work-support and is arranged in a recess in the work-support so that it presents a feeding surface to the work similar to the surface of the work-support. (See Fig. 4.) The feed-bar 32 is at its lower end in the form of a foot 55 provided on its under surface with teeth to grip the work. It is also provided with a guide 56 secured to the feed-bar by a screw 57 and having guiding feet 58, 59; the foot 58 tending to hold the material against the gage 30 and the foot 59 holding the material down as the work is fed forward. (See Fig. 5.) This insures feeding the work evenly and prevents any curling of the edge of the work. The presser-foot 34, which holds the work between the feeding movements, has its lower end bent around so that it will engage the work at a point adjacent to the feeding members.

For operating the feeding means and the presser-foot, means are provided for moving the feed-bar downwardly into engagement with the work and against the feed-roll 33, then forwardly to feed the same, then upwardly to release it from the work, then rearwardly and downwardly to again engage the work for the feeding movement and means are provided for moving the presser-foot downwardly to engage the work when the feed-bar reaches the end of its feeding movement and to hold the work while the feed-bar is moving rearwardly to

the point of beginning of the next feeding movement, when the presser-foot is then raised. These means consist of a feed-shaft 60 and a lift-shaft 61, the former accomplishing the forward movement of the feed-bar and the latter the upward and downward movement of both the feed-bar and the presser-foot. The feed-shaft 60 is journaled at one end in a bearing 62 in the frame 10 and at the other end in a bearing 63 in the end of the overhanging arm 12. On the forward end of the feed-shaft 60 is mounted an extension 64, having one end in the form of a split collar 65 adapted to receive a screw 66 for securing the extension to the feed-shaft. The other end of the extension is in the form of a housing 67 within which the feed-bar 32 reciprocates. When the feed-shaft 60 is oscillated the housing 67 carrying the feed-bar 32 is turned forward and back thus feeding the material.

In order to impart the forward and rearward movement of the feed-bar, the feed-shaft 60 is oscillated through suitable connections by the rotation of the main shaft 20. Between the pulley 21 and the frame 10 an eccentric 70 is secured on the main shaft, either as an integral part of the pulley 21 or independent of it. (Fig. 6.) Through the upper part of the frame 10 at 71 is journaled a rock-shaft 72 upon one end of which is mounted a split collar 73 secured by a screw 74 and carrying a short arm 75 which is pivotally connected at its end by a pin 76 in a yoke 77 on an arm 78, the lower end of which carries a strap 79 surrounding the eccentric 70. When the main shaft is rotated, the movement of the eccentric 70 within the strap 79 causes the arm 78 to be moved upwardly and downwardly and thereby to impart a rocking movement to the rock-shaft 72. The feed-shaft is oscillated by the rock-shaft through the following means. Upon the other end of the rock-shaft 72 is fixedly mounted an arm 82 which has its two ends 100 in the form of split collars; the lower collar 83 being tightly held upon the rock-shaft 72 by means of a screw 84 and the upper one 85 upon a pin 86 by a screw 87. Upon the feed-shaft 60 is secured an arm 90 which is similar in construction to the arm 82 in having its two ends formed into split collars; one of which 91 surrounds the feed-shaft 60 and is held in fixed engagement with said shaft by a screw 92 and the other of which 93 carries 110 a pin 94 which is held tightly by means of the screw 95. The arm 82 on the rock-shaft 72 and the arm 90 on the feed-shaft 60 are connected by a link arrangement made up of two arms 96 and 97, the former loosely mounted on the pin 94 and the latter mounted in a similar manner on the pin 86. The free ends of these two pins 94 and 86 have enlarged heads in order to retain the arms 96 and 97 in place upon the pins. At their 115 120 125 130

- lower ends the two arms are connected by a common pin 98 which is secured in a split collar 99 on the end of the arm 97 by a screw 100 but is loose in the end of the arm 96 to permit of relative pivotal movement of the two arms 96 and 97. By means of the foregoing arrangement of the connections between the rock-shaft and the feed-shaft, a rocking movement is imparted to the latter 5 by the rocking movement of the former and the relative amount of the movement imparted thereby will depend upon the position of the two arms 96 and 97 and the resultant movement of the pin 98. The arms 10 82, 96 and 97 are of approximately the same length and in consequence of this fact and of the arrangement of the arms, the movement imparted to the feed-shaft by the movement of the rock-shaft increases as the 15 lower end of the arm 97 is moved away from the center of the rock-shaft 72. If the arm 97 is in alinement with the arm 82, then the pin 98 is centered on the rock-shaft and the movement of the latter will impart no movement 20 whatever to the feed-shaft because the pin 98 will merely turn in the end of the arm 96 and not move it. By moving the end of the arm 97 around the pin 86 as a pivot and away from the center of the rock-shaft 25 72, the resultant movement of the feed-shaft is increased in proportion to the distance the pin 98 is removed from the center of the rock-shaft.
- In order to adjust the position of the arms 30 96 and 97 and thereby regulate the amount of the rocking movement of the feed-shaft 60 and consequently the length of the feeding movement of the feed-bar 32, I provide adjustable means for turning the arms 96 35 and 97 downwardly and upwardly away from the center of the rock-shaft 72. Preferably these means comprise a screw 105 threaded through a boss 106 fastened to the lower part of the arm 97, the end of the screw bearing against a portion of the split collar 83 secured to one end of the rock-shaft. A coiled spring 107 attached at one 40 end to the split collar 91 on the feed-shaft 60 and at the other end to a pin 109 set in the end of the pin 98 serves to hold the arms 96 and 97 in a retracted position and the end 45 of the screw 105 in engagement with the collar 83. By turning the screw 105 in one direction or the other the arms 96 and 97 may be thrown away from or toward the center 50 of the rock-shaft 72 and the length of the feeding movement thereby regulated. A set nut 110 is provided to hold the screw in its 55 adjusted position.
- 60 The upward and downward movements of the feed-bar and presser-foot are accomplished by the oscillation of the lift-shaft 61 which is oscillated from the main shaft in the following manner. An eccentric 115 65 is secured to the main shaft 20 and is in-
- closed by a split-strap 116 held together by a screw 117. The strap forms a part of an arm 118 having its upper end in the form of a yoke 119. Pivotedly connected to the yoke by a pin 120 is a short arm 121 which is carried by a split collar 122 fastened to the lift-shaft 61. The rotation of the main shaft and eccentric reciprocates the arm 118 longitudinally thereby oscillating the lift-shaft 61 through the medium of the short 75 arm 121.
- For raising and lowering the feed-bar and presser-foot at the appropriate times the following means are provided. Upon the end of the lift-shaft is secured a split collar 80 125 carrying a short arm 126 having pivotally mounted on its end a link 127 the upper end of which is forked to receive and form a loose bearing for a block 128 carried on a pin 129 which forms a part of a split collar 130 fastened to the upper end of the feed-bar 32 by a screw 131. The feed-bar is not connected to the link 127 and the block 128 is loosely mounted in the forked end of the link. To keep the feed-bar 32 in its lowermost position, there is arranged on the link 85 a hood 133 which curves over the top of the feed-bar and acts as a buttress for a small coiled spring 135 set in the top of the feed-bar. This spring exerts a downward pressure 90 upon the feed-bar to keep it in tight engagement with the work, yet permit it to retract when a seam in the work or a thicker portion of the work passes under the feed-foot. Between the collar 130 and the feed-bar housing 67 may be arranged a washer 136, preferably of fibrous material, to withstand wear, and by regulating the position 95 of the feed-bar 32 in the collar 130, the feed-bar can be adjusted to a fine degree so that the feed foot will grip the material when feeding without exerting undue pressure upon the feed roll.
- The presser-foot 34 is pivoted at 140 on a rod 141 loosely journaled in a depending 100 part 142 of the overhanging arm 12. Above the pivot point the presser-foot extends upwardly in the form of a flat finger piece 143 which may be utilized for lifting the presser-foot when desired, as for instance, 105 when removing partially finished work from the machine. A spring 145 is set in an arm 146 extending outwardly from the arm 12 and bears against the finger piece 143 thereby holding the presser-foot in a lowermost 110 position. For regulating the pressure of the spring 145 a screw 147 bearing against one end of the spring may be provided with a set-nut 148 for holding the screw in any 115 adjusted position.
- 120 For raising the presser-foot by the lift-shaft, the split collar 125 is provided with a lug 150 secured to its under side by a screw 151, which lug engages an adjustable screw 152 set transversely in the presser-foot above 125 130

the pivot point. The rocking movement of the split collar 125 thereby causes the presser-foot to be raised at appropriate times. By adjusting the screw 152 the timing of 5 the operation of the presser-foot can be made exact.

As the work is fed through the machine by the action of the feeding means, it passes by the plow which turns over the edge ready 10 for the action of the fold-pressing means, which presses down upon the body-portion of the material the turned over edge. This action is intermittent and takes place between the feeding movements and while the 15 work is held stationary by the presser-foot. As heretofore stated, one very important feature of my invention resides in the convexly curved work-support and fold-pressing means adapted to coöperate therewith. Various 20 means may be provided for pressing down the fold in conjunction with the curved work-support and one form of means is shown in the drawings comprising a reciprocating hammer 35 having a fold-pressing 25 surface which is parallel to the surface of the work-support. (See Fig. 8.) Preferably the hammer 35 reciprocates in a straight line, oblique to the main longitudinal axis of the machine but perpendicular to the 30 surface of the work-support 25. The hammer, in the embodiment illustrated in the drawings, is mounted on the lower end of a rod 160 which is movably supported in a block-bearing 161 secured to the end of the overhanging arm 12 and reciprocates therein. 35

Any suitable means may be provided for operating the hammer and one such is shown and comprises the following. On top of the overhanging arm 12 and slightly off center 40 in a direction away from the operator is arranged a rock-shaft 165 in suitable bearings carried by brackets 166 and 167 which constitute parts of the overhanging arm 12. The rock-shaft 165 is operated from the lift-shaft 61 but in an opposite direction by 45 means of two short arms 170 and 171, the former mounted on the lift-shaft and the latter on the rock-shaft 165, and a link 172 connecting the two arms. Each of the arms 50 170 and 171 is of the same construction, comprising a split collar part 173 at one end, with a screw 174 for fastening the arm to its respective shaft and with a split collar 176 at the end for receiving a pin 178 to hold one 55 end of the link 172. In view of the fact that the arms 170 and 171 project in opposite directions from the two shafts, the rock-shaft 165 is oscillated in a direction reverse to that of the lift-shaft which is necessary so 60 that the hammer may operate at the same time that the presser-foot is lowered.

Upon a transverse shaft 180 rotatably mounted in a suitable bearing 181 on the upper arm 12 is arranged a bell-crank lever 65 183, one end of which carries a screw 185

threaded therethrough. The screw 185 is provided with a bore extending from its end nearly to its head within which is mounted a fairly stiff coil spring 184 which engages the end of the hammer rod 160. The other 70 end of the bell-crank lever 183 is connected by a pin 186 to a link 187 which in turn is connected to the free end of an arm 188 by a pin 189, the arm 188 being secured to the rock-shaft 165 by means of a split-collar 75 190 and screw 191. The link 187 is in the form of two yokes arranged at right angles to each other, each yoke carrying a cross-wise pin upon which the member to which the particular yoke is connected is pivotally 80 mounted. The link therefore acts as a universal joint connection between the bell-crank lever 183 and the arm 188, which move in circles at right angles to each other.

By means of these various connections the 85 rocking motion of the rock-shaft 165 is transmitted through the arm 188, link 187, bell-crank lever 183, screw 185 and spring 184 to the end of the hammer rod 160 to drive it downwardly to press the material. 90 As the rod 160 is not connected to the spring 184, I provide suitable means for retracting it or moving it upwardly when the screw 185 is moved upwardly, such, for instance, as a spring 195 connected under tension at one 95 end to a pin 196 set on the back side of the arm 12 and at the other end to a pin 197 set in a collar 198 fastened to the hammer rod 160. The spring being under tension at all times serves to keep the rod in an 100 uppermost position with its top end in engagement with the spring 184. The screw 185, it will be noticed, is adjustable in the bell-crank lever, being held in adjusted position by a set-nut 199, whereby the amount 105 of pressure exerted by the spring 184 and hence by the hammer on the material in the pressing operation may be regulated. By means of the spring 184 I secure a yielding hammer which accommodates itself to varying 110 thicknesses of material.

It will be noticed that the hammer is in plan outline approximately a quadrant of a circle and that it is mounted on the rod 160 near the point corresponding to the center of the circle of which it is a quadrant. (See Fig. 11.) The arrow in Fig. 11 indicates the direction of and normal line of feed. The front edge 200 of the hammer nearest the operator is normally approximately 115 at right angles to the line of feed.

In folding outside or convex curves of small radii, the work is pivoted at a point in front of the hammer and toward the operator, in which case it is desirable to extend 120 the pressing surface of the hammer nearer to the operator in order that the entire fold may be pressed. For this purpose I have provided means for swinging the hammer toward the operator through an arc of approximately 125 130

- proximately forty-five degrees, said means comprising a finger-piece 202 set in the collar 198 on the hammer rod whereby the operator by pressing downwardly upon the 5 finger-piece turns the hammer into the desired position. This can be accomplished during the operation of the machine and without interfering with it. By thus turning the hammer the pressing surface is 10 turned nearer to the operator as shown in Fig. 11 by the dotted lines. When the operator releases the finger-piece, the spring 195 returns the hammer rod 160 to its normal position.
- 15 The turning of the hammer as above described throws the curved pressing surface out of parallelism with the curved surface of the work-support, but as the area of the hammer is comparatively small compared 20 with the area of the work-support the slight difference between the two pressing surfaces which results is compensated for by the facts that there is a surplus of material in the folded over portion in convex curves which 25 folds in puckers and therefore forms a thicker fold and that the hammer yields.
- As my machine is designed to operate at a high speed, I have found it preferable to counterbalance the hammer operating mechanism which is located entirely on one side of the rock-shaft 165 by a counterweight 205 carried on a short arm 206 secured to the rock-shaft 165 by a split-collar 207 and screw 208. As a result the machine is evenly 30 balanced and will operate at a very high speed without vibration.
- In folding the edges of concave or inside curves, a cutting or slitting of the edge to be folded is essential and for this reason means 35 are provided for slitting the edge of the material when necessary. These means comprise a knife-block 36 provided with a slot 210 whereby it may be adjustably fastened to the top of the lower arm 11 by a screw 40 212. Arranged to coöperate with the knife-block is a knife blade 37 carried by a vertical knife-bar 213, and provided with a shearing edge and a downwardly projecting beveled guide 214. The knife blade is 45 provided with a slot 215 adapted to receive a screw 216 whereby it may be adjustably secured to the knife-bar. The latter is movably mounted in a block or bearing 217 which may be attached either to the block 50 161 or to the end of the arm 12. Movably mounted in the bearing block 217 is a guide-rod 219 having a split end 220 in which is fastened by a screw 221 a cross-bar 222 integral with a split collar surrounding and 55 fastened to the top of the knife-bar 213 by a screw 223. The knife-bar, guide rod and cross-bar thereby reciprocate as a unit and the guide rod prevents any twisting or turning of the knife-bar and keeps the knife blade 60 in alignment with the knife-block.

The knife blade is operated from the rock-shaft 165 when desired, through the following means. Upon the end of the rock-shaft 165 is fastened a short arm 225 extending upwardly and obliquely toward the operator, the arm being of the same general form as other arms in this machine having a split collar 226 at one end whereby it is fastened on the rock-shaft and a split collar 228 at the other end to receive a pin 230 upon 70 which is pivotally mounted a short arm 232. The lower end of the latter arm is pivotally connected by a pin 233 to a link 234 which is in turn pivotally connected to the cross-bar 222. The pin 233 also pivotally connects 80 to the arm 232 and link 234 a bar 235 the other end of which is pivotally connected to a depending bar 236, the lower end of which is fastened to one end of a rod 238 running longitudinally the machine on the side away 85 from the operator, which is rotatably journaled in brackets 240 and 241 springing from the upper arm 12. The other end 242 of the rod 238 is turned back and under the bracket 241 which acts as a stop to limit the 90 rotation of the rod in one direction. Collars 243 and 244 are arranged on the rod 238 and fastened thereto on either side of the bracket 240 to prevent longitudinal movement of the rod. A spring 245 fastened at 95 one end to the turned end 242 of the rod 238 and at its other end to the frame of the machine, holds the bar in the position shown in Fig. 2.

The normal position of the knife operating parts is illustrated in Fig. 3 where it will be observed the pin 233, which is the pivot point of connection of the arm 232, the link 234 and the bar 235 is on center with the center of the rock-shaft 165. Any rocking movement of that shaft does not, therefore, change the location of the pin 233 and has no effect upon the knife operating mechanism and in consequence, the knife blade 37 remains immovable.

Upon the rod 238 is fixed a lever 250 to the free end of which a treadle or other suitable operating device is designed to be attached by a rod 251 whereby the end of the lever may be depressed, turning the 105 rod 238 against the tension of the spring 245. The immediate result of turning the rod 238 is to throw the pin 233 away from the center of the rock-shaft 165 into the position of the parts shown in Fig. 10 and when the 110 parts are in that position, the rocking movement of the rock-shaft 165 produces a reciprocating movement of the knife-bar and knife blade which results in cutting the edge of the material between the plow and the 115 gage where the knife-block and knife blade are located.

By means of the above construction, the operator absolutely controls the knife mechanism and throws it into and out of opera- 120 125 130

tion by merely pressing down a treadle and releasing it.

Heretofore in most folding machines the knife blades have been so arranged as to cut 5 slits which were perpendicular to the normal line of feed, that is, the blades were arranged parallel to the longitudinal axis of the machine. Where straight edges were cut the slits were perpendicular to the edge, 10 but in cutting the edges on concave or inside curves of small diameter, the cuts were oblique to the edge because in folding such curves it is necessary to pivot the work which presents the edge to be cut at an angle 15 to the knife and not perpendicular to it. This has resulted in choppy and uneven work on such curves.

To avoid this, I have arranged my knife at an angle of approximately fifteen degrees 20 to the main horizontal axis of the machine with the front of the knife nearer to the operator. By so doing I have found that I get slits on inside curves of small radii which are approximately perpendicular to 25 the edge of the curve and thereby I secure folds on such curves which are uniform, neat and finished with a smooth curving edge. Although I have specified the angle at which the knife is set and the angle of 30 the shearing edge of the knife-block to be approximately fifteen degrees, I do not limit myself to that angle as in different classes of work other angles greater or less than fifteen degrees may be found preferable.

35 I have described my slitting device herein because it constitutes a part of my improved machine but I do not desire to claim the invention shown and disclosed thereby since it is described and claimed in an application 40 filed by me June 25, 1919, Serial No. 306,627.

As heretofore stated, one of the most important features of my invention resides in the provision of a convexly curved work-support and pressing means having a pressing surface parallel to the surface of the work-support. By means of this construction 45 the edge to be folded is turned over into an acute angle with the surface of the work-support, which thereby relieves the strain on 50 the edge to prevent stretching of the edge and insures the laying of a uniform, even and smooth fold. Referring to Fig. 8 showing the work-support and hammer in their relation to the plow or fold turning 55 device, it will be noticed that the rearmost edge of the plow adjacent to the curved work-support and hammer is substantially vertical and the lines of that edge and of the work-support make an acute angle. 60 Consequently, as the material is fed past the plow the turned over edge is at an acute angle with the body-portion of the work which is supported on the curved work-support and when the hammer operates to 65 press down the fold upon the body-portion

the pressing operation is completed without placing any substantial strain upon the turned over edge of the material. The reason for this will be apparent when it is considered that it is much easier to fold 70 the edge of the material if the body-portion be held on a curved support and the edge merely turned over, and this is the principle upon which this feature of my invention is based. 75

It is to be observed that my folding machine employs comparatively few parts and is extremely simple both in construction and operation. Because of its balanced and compact construction it is capable of very 80 high speed thereby producing finished work with great rapidity. Furthermore, its operation at a high speed is without vibration and practically noiseless, thereby reducing the strain on the operator. 85

It is to be understood that my invention may be embodied in other forms of construction than that shown and described and it is my intention to claim it broadly except where specifically limited in the following 90 claims.

What I claim is:—

1. In a folding machine, the combination of means for feeding the material through the machine, means for turning over the 95 edge to be folded, means for pressing the edge to be folded down upon the body-portion of the material and a work-support for holding the material being operated upon, said work-support being curved transversely 100 to the line of feed beginning at the line of fold of the material.

2. In a folding machine, a convex work-support for the material to be operated upon, means for feeding the material 105 through the machine, means for turning over the edge to be folded and means for pressing the edge to be folded down upon the body-portion of the material; said work-support being convex at all points beginning 110 with the line of fold of the material.

3. In a folding machine, the combination of a work-support curved transversely to the line of feed, means for feeding the material through the machine, means for turning over the edge to be folded and means for pressing the edge to be folded, the pressing surface of said pressing means being parallel to the curved surface of said work-support. 115

4. In a folding machine, the combination of a convex work-support for the material to be operated upon, means for feeding the material through the machine, means for turning over the edge to be folded and means for pressing the edge to be folded down upon the body-portion of the material, the pressing surface of said pressing means being concaved and parallel to the convex 125 surface of said work-support. 130

5. A folding machine having, in combination, a cylindrically curved work-support, the center axis of said curve being parallel to the line of feed, means for turning over the edge to be folded and means for pressing down the edge to be folded, the pressing surface of said last mentioned means being parallel with the surface of said curved work-support.

10. 6. In a folding machine, the combination with means for feeding the material step by step and means for turning over the edge to be folded of a work-support having a convex surface constituting a portion of a cylinder the axis of which is parallel to the line of feed and a hammer for pressing down the turned over edge to be folded, said hammer having a concaved pressing surface which is parallel to the convex surface of the work-support and said hammer reciprocating in a line perpendicular to the curved surface of the work-support.

15. 7. In a folding machine the combination with means for feeding the material through the machine and means for turning over the edge to be folded of a curved work-support and means for pressing down the turned over edge of the material upon the body-portion, said pressing means having a concaved surface of the same curvature as that of the convex surface of the work-support.

20. 8. A folding machine comprising a work-support curved transversely to the line of feed, means for feeding the work, means for turning over the edge to be folded and means for pressing down the said edge, said pressing means being adapted to reciprocate in a straight line at an angle to the main axis of the machine and having a pressing surface parallel to the surface of said work-support.

25. 9. A folding machine comprising a work-support curved transversely to the line of feed, means for feeding the edge to be folded, and a hammer for pressing down the said edge, said hammer being set at an angle to the main axis of the machine and having a pressing surface parallel to the curved surface of said work-support.

30. 10. A folding machine comprising a work-support curved transversely to the line of feed, means for feeding the work, means for turning over the edge to be folded, and a reciprocating hammer for pressing down the said edge, said hammer being adapted to move in a straight line inclined to the main axis of the machine.

35. 11. A folding machine comprising a fixed work-support having a cylindrically curved surface, means for turning over the edge to be folded and means for pressing down said edge; said pressing means having a pressing surface parallel to the surface of said work-support.

40. 12. A folding machine comprising a work-support having a cylindrically curved surface, means for turning over the edge to be folded and reciprocating means for pressing down said turned over edge upon the body-portion of the material; said pressing means having a pressing surface parallel to the surface of said work-support.

45. 13. A folding machine comprising a work-support having a cylindrically curved surface, the axis of said curve being parallel to the line of feed of the material, means for turning over the edge to be folded, a hammer for pressing down said turned over edge upon the body-portion of the material, and means for reciprocating said hammer in a line inclined to the main axis of the machine and perpendicular to the surface of said work-support.

50. 14. A folding machine comprising a work-support having a cylindrically curved surface, means for feeding the material to be folded in a line parallel to the axis of curvature of said work-support, means for turning over the edge to be folded, a hammer for pressing down said edge upon the body of the material, said hammer having a pressing surface parallel to the curved surface of said work-support, and means for reciprocating said hammer in a line perpendicular to said work-support.

55. 15. A folding machine comprising a work-support having a curved surface, means for feeding the material to be operated upon, means for turning over the edge to be folded, a hammer for pressing down the said edge upon the body of the material, said hammer having a pressing surface parallel to the curved surface of said work-support, and means for reciprocating said hammer.

60. 16. A folding machine comprising a work-support having a curved surface, means for feeding the material to be operated upon, means for turning over the edge to be folded, a hammer having a pressing surface parallel to the surface of said work-support, said hammer being arranged to reciprocate in a line perpendicular to the curved surface of said work-support and inclined to the main horizontal axis of the machine, and means for reciprocating said hammer to press down said turned over edge upon the body of said material.

65. 17. A folding machine having, in combination, a convexly curved work-support, means for feeding the work through the machine, means for folding the edge thereof, and means for pressing down the folded edge; said feeding means and said pressing means each having work-engaging surfaces parallel to the surface of said work-support.

70. 18. A folding machine having, in combination, a convexly curved work-support, the

axis of said curve being parallel to the normal line of feed, means for feeding the work, means for folding the edge of the work and means for pressing down said folded over 5 edge; all of the work-engaging surfaces of said feeding and said pressing means being parallel to the curved surface of said work-support.

19. A folding machine having, in combination, a work-support curved transversely to the line of feed, means for feeding the work, means for turning over the edge to be folded and means for pressing down said edge; said feeding means and said pressing 10 means having work-engaging surfaces which are parallel to the curved surface of said work-support.

20. A folding machine having, in combination, a cylindrically curved work-support, 20 means for feeding the work, means for turning over the edge to be folded and a hammer for pressing down upon the body-portion of the work said turned over edge; said feeding means and said hammer having all work- 25 engaging surfaces parallel to the surface of said work-support.

21. A folding machine comprising a convexly curved work-support, means for turning over the edge to be folded and yieldable 30 means for pressing down said edge, said yieldable pressing means having a curved pressing surface parallel to the surface of said work-support.

22. A folding machine comprising a work- 35 support curved transversely to the line of feed, means for feeding the work, means for turning over the edge to be folded, and yieldable means for pressing down said edge, said yieldable means having a curved press- 40 ing surface parallel to the surface of said work-support.

23. A folding machine comprising a work- support convexly curved transversely to the line of feed, means for feeding the work, 45 means for turning over the edge to be folded, and a yieldable hammer for pressing down the said edge, said hammer having a curved pressing surface parallel to the surface of said work-support.

50 24. A folding machine comprising a work-support having a cylindrically curved surface, means for turning over the edge to be folded and a reciprocating hammer for pressing down said edge; said hammer being 55 rotatable on its axis in order to advance its pressing surface near to the operator when desired.

25. A folding machine comprising a work- support having a cylindrically curved sur- 60 face, means for turning over the edge to be folded and a reciprocating hammer for pressing down said edge, said hammer having a pressing surface parallel to the surface of said work-support and being capable of 65 rotation on its axis at the will of the operator

without interfering with the operation of the machine.

26. A folding machine comprising a convexly curved work-support, means for turning over the edge to be folded and means 70 for pressing down said edge, said pressing means having a curved pressing surface parallel to the surface of said work-support and being rotatable in order to advance the pressing surface of said means toward the 75 operator to facilitate folding on convex curves.

27. A folding machine comprising a cylindrically curved work-support, means for feeding the work, means for turning over 80 the edge to be folded, and spring-actuated means for pressing down said edge, said spring-actuated means being rotatable at the will of the operator, without interfering with the operation of the machine, in order to advance the pressing surface of said pressing means toward the operator to facilitate the 85 folding of convex curves.

28. A folding machine comprising a work-support curved cylindrically and transversely to the line of feed, means for feeding the work, means for turning over the edge to be folded and means for pressing down said edge, said pressing means being 90 rotatable at the will of the operator, without interfering with the operation of the machine, in order to advance the pressing surface of said pressing means toward the operator to facilitate the folding of convex 95 curves.

29. A folding machine comprising a curved work-support having a cylindrically curved surface, means for feeding the work, means for turning over the edge to be folded and a yieldable hammer for pressing down 100 said edge, said yieldable hammer being rotatable at the will of the operator in order to advance its pressing surface nearer the operator to facilitate the folding of convex 105 curves.

30. A folding machine comprising a convexly curved work-support, means for feeding the work, means for slitting the edge to be folded at the will of the operator, means for turning the edge to be folded and means having a curved pressing face for pressing down said edge.

31. In a folding machine, the combination with folding instrumentalities of a work-support having a convex surface adapted to 120 support the body-portion only of the material being folded, said convex surface beginning at the line of fold of the material in order that the body-portion of the material may lie in the machine at an angle of 125 less than one hundred and eighty degrees with the edge to be folded over before said edge is turned over.

32. In a folding machine, the combination with folding instrumentalities of a work- 130

support having a cylindrically curved surface, the axis of said curve being parallel to the line of feed of the material, said curved surface beginning at the line of fold of the material in order that the body-portion of the material may lie in the machine at an angle of less than one hundred and eighty degrees with the edge to be folded over before said edge is turned over.

10. 33. In a folding machine, the combination with folding instrumentalities of a work-support having a cylindrically curved surface, the axis of said curve being parallel to the line of feed of the material, said curved surface beginning at the line of fold in order that the angle between the body-portion of the material and the turned over edge of the material before it is pressed down on the body-portion may be an acute angle in order to prevent stretching of the edge of the material by the pressing operation.

15. 34. In a folding machine, the combination with folding instrumentalities of a forwardly extending arm having a flat horizontal top adjacent its end, and a work-support having a cylindrically curved surface, the axis of said curve being parallel with the

line of feed of the material, mounted on the end of said arm, said curved surface beginning at the line of fold of the material in order that the body-portion of the material may lie in the machine at an angle of less than one hundred and eighty degrees with the edge to be folded over before said edge is turned over.

35. In a folding machine, the combination with folding instrumentalities, of a work-support having a supporting surface divided on the line of fold of the material into a flat portion and a curved portion, the angle between the two surfaces being less than one hundred and eighty degrees.

36. In a folding machine, the combination with folding instrumentalities, of a work-support having a curved portion adapted to support the body-portion of the material being folded and a flat portion for supporting the edge of the material before it is folded, the angle between said curved and said flat portions being less than one hundred and eighty degrees.

In witness whereof I hereunto set my hand this nineteenth day of May, 1919.

WILLIAM F. LAUTENSCHLAGER.
